UNITED STATES PATENT OFFICE

AMBROSE D. OLDS, OF WICHITA, KANSAS, ASSIGNOR TO THE COLEMAN LAMP & STOVE COMPANY, OF WICHITA, KANSAS

DESIGN FOR A COFFEE MAKER

Application filed January 15, 1932. Serial No. 42,498. Term of patent 7 years.

To all whom it may concern:

Be it known that I, AMBROSE D. OLDS, a citizen of the United States of America, residing at Wichita, in the county of Sedgwick and State of Kansas, have invented a new, original, and ornamental Design for a Coffee Maker, of which the following is the specification, reference being had to the accompanying drawings, forming a part thereof.

Fig. 1 is a front elevational view of the coffee maker, showing my new design.

Fig. 2 is a cross sectional view on the line 2—2 of Fig. 1, and

Fig. 3 is a diagrammatic top plan view of the coffee maker, on a reduced scale.

I claim:

The ornamental design for a coffee maker as shown.

In testimony thereof I affix my signature.

AMBROSE D. OLDS.
